[57] CLAIM

The ornamental design for a peeling utensil for hard boiled eggs, as shown and described.

DESCRIPTION

FIG. 1 is a perspective view of a peeling utensil for hard boiled eggs showing my new design;

FIG. 2 is a plan view of the preferred design;

FIG. 3 is a bottom view thereof;

FIG. 4 is a side view thereof, the opposite side being a mirror image thereof;

FIG. 5 is a view from the left side of FIG. 4;

FIG. 6 is a view from the right side of FIG. 4.
